(57) **CLAIM**

The ornamental design for a cleat for a boat, as shown and described.

DESCRIPTION

FIG. 1 is a perspective view of a cleat for a boat, showing the new design;

FIG. 2 is a left side elevational view of the cleat for a boat, with the right side elevational view (not shown) being a mirror image of the left side view;

FIG. 3 is a front elevational view of the cleat for a boat, with the rear elevational view (not shown) being a mirror image of the front elevational view;

FIG. 4 is a top view of the cleat for a boat; and,
FIG. 5 is a bottom view of the cleat for a boat taken along line 5-5 in FIG. 3.

The broken lines in the drawings depict portions of the cleat for a boat that form no part of the claimed design.

1 Claim, 5 Drawing Sheets
